UNITED STATES PATENT OFFICE.

EMANUEL E. NORQUIST, OF KANSAS CITY, MISSOURI.

METAL TANK.

SPECIFICATION forming part of Letters Patent No. 769,271, dated September 6, 1904.

Application filed March 9, 1904. Serial No. 197,216. (No model.)

To all whom it may concern:

Be it known that I, EMANUEL E. NORQUIST, a citizen of the United States, residing at Kansas City, in the county of Jackson and State 5 of Missouri, have invented certain new and useful Improvements in Metal Tanks; and I do declare the following to be a full, clear, and exact description of the invention, such as will enable others skilled in the art to which it applies 10 to make and use the same, reference being had to the accompanying drawings, and to the figures of reference marked thereon, which form a part of this specification.

My present invention relates to metal tanks, 15 and has for its object to provide a means for bracing the upper rim of the tank in such a manner as to render the use of bolts or rivets unnecessary without decreasing the rigidity of the tank or rendering it liable to collapse. 20 In this way a tank may be constructed with quite a saving of time, labor, and expense in comparison with the ordinary method of construction.

My invention will presently be more fully 25 described, and pointed out in the claim, reference being had to the accompanying drawings, forming part of this specification, in which like reference-numerals refer to like parts throughout the several views, and in which— 30 Figure 1 is a side view of a tank constructed according to my method, parts being broken away to show the pipe and inner surface of the tank. Fig. 2 is an enlarged detail view of a portion of the tank and pipe. Fig. 3 is 35 an enlarged detail view of the pipe, showing the means for joining the ends of same.

Referring more in detail to the drawings, 1 is the outer casing or drum of a metal tank, near the upper edge of which is provided a 40 corrugation 2. Above corrugation 2 casing

1 is bent or corrugated to form a semicircular groove or recess 3, in which is placed a pipe 4. Fitting within the opening in one end, 5 or 6, of pipe 4 and held in place by means of an internal projection 7 or 8 in said pipe 45 is a pin 9. When pipe 4 is placed in the groove 3, the portion of pin 9 projecting from one end of the pipe is inserted in the opening in the opposite end thereof and forced against an internal projection within 50 that end as said ends of the pipe are brought together. The upper edge of the casing is then made to fit snugly around pipe 4, forming a continuous brace for the top of the tank, thereby making it firm and substantial. The 55 bottom of the tank may be constructed in any suitable manner, as my invention only has reference to the parts described.

I do not wish to be understood as limiting myself to the exact details of structure herein 60 shown and described, inasmuch as the same may be varied without departing from the spirit of my invention.

Having thus described my invention, what I claim as new therein, and desire to secure by 65 Letters Patent, is—

In a metal tank, the combination of a shell having a suitable bottom and having corrugations as its top, a metal tube having internal projections near its ends, seated in a groove 70 formed by said corrugations, and a pin mounted in the ends of said tube and adapted to bear against said projections.

In testimony whereof I affix my signature in presence of two witnesses.

EMANUEL E. NORQUIST.
